X-RAY FILM DUPLICATOR/SUBTRACTOR UNIT

Richard L. Evenson, and William J. Overton, Portland,
Oreg., assignors to Northwest Refining Company, Port-
land, Oreg.

Filed Mar. 29, 1974, Ser. No. 455,989

Term of patent 14 years

Int. Cl. D16—04

U.S. Cl. D61—1 Q

FIG. 1 is a front perspective view of an X-ray film duplicator/subtractor unit showing our new design;

FIG. 2 is a rear perspective view thereof; and

FIG. 3 is a front perspective view thereof showing the lid in a partially opened condition.

We claim:

The ornamental design for an X-ray film duplicator/subtractor unit, as shown and described.
